UNITED STATES PATENT OFFICE.

FRANK AMOS JOHNSON, OF NEW HAVEN, CONNECTICUT, ASSIGNOR TO SIGNATURE COMPANY, OF NEW YORK, N. Y., A CORPORATION OF NEW YORK.

MULTIPLE-WRITING MACHINE.

Application filed September 30, 1919. Serial No. 327,469.

To all whom it may concern:

Be it known that I, FRANK AMOS JOHNSON, a citizen of the United States, and resident of New Haven, county of New Haven, 5 and State of Connecticut, have invented certain new and useful Improvements in Multiple-Writing Machines, of which the following is a specification.

This invention relates to multiple writing machines in which a signature or other written matter is simultaneously written upon a group of documents under the control of a master staff or monitor. The general object of this invention is to provide an improved 10 construction, combination and arrangement of parts in a machine of this character, whereby the documents, such for example as checks may be taken from different stacks or sources, arranged in predetermined 15 groups, fed into position to be written upon, and finally conveyed from the writing pens to be restacked or grouped in any desired arrangement which is usually the same as that from which they were segregated and 20 formed into predetermined groups for being written upon. One of the objects of the present invention is to provide improved means for feeding checks from a plurality 25 of stacks and arranging them in groups to 30 correspond to the group arrangement of the pens by which they are to be written upon. Another object is to provide improved means 35 for correlating the check-feeding and check-stacking operations with the operation of the pen group. Other and more specific objects of invention will appear in the specification and be pointed out in the claims, reference being had to the accompanying drawings which exemplify my invention and in 40 which,—

Figure 1 is a side elevation of a machine embodying the principles of the present invention;

Figure 2 is a plan view of the same in reverse position to that shown in Figure 1;

Figure 3 is an end elevation of the same, taken from the right according to Figure 1;

Figure 4 is a side elevation of the machine corresponding to the left end of Figure 2;

50 Figure 5 is a side elevation, on an enlarged scale, of the upper right hand portion of Figure 1, with the cover plate removed;

Figure 6 is a sectional elevation, on an enlarged scale, on the line 6—6, Figure 3; 55

Figure 7 is a sectional elevation, on an enlarged scale, on the line 7—7, Figure 3;

Figure 8 is a sectional elevation, on an enlarged scale, on the line 8—8, Figure 1;

Figure 8^a is a sectional elevation on an enlarged scale, on the line 8^a—8^a, Figure 8;

Figure 9 is a sectional elevation of the carriage, on an enlarged scale, on the line 9—9, Figure 2; 65

Figures 10 and 11 are sectional elevations similar to Figure 9, with the grippers in changed positions;

Figure 12 is a sectional elevation, according to the line 12—12, Figure 2, showing the 70 receiving or stacking mechanism on an enlarged scale;

Figure 13 is a longitudinal sectional elevation of a stacking device for checks which are too thin to be handled in the usual 75 way;

Figure 14 is a fragmentary top plan view of the stacking box;

Figure 15 is a similar top plan view showing parts in changed positions. 80

According to the embodiment of my invention shown on the drawings, the main frame of the machine, as shown in Figure 1, includes three pairs of uprights 1, 2, and 3. Throughout the following description, 85 as that toward which the documents move in their passage through the machine. Said documents will therefore be considered as entering the machine at the rear end. The 90 right side will therefore be considered that on the observer's right as he faces forward, the left side being toward his left hand as he faces forward. Surmounting the rear uprights 1, are left and right side frames 95 4 and 5, the forward ends of said side frames being connected by left and right side bars 6 and 7 (see Figures 1, 4, and 8) to the rear end of the main bed plate 8 which surrounds the paired uprights 2 and 3. As 100 shown in Figure 4, a crank 9 provided with a hand grip 10, is journaled upon a stud 11 which is mounted in the side frame 5. Also journaled on the stud 11 and adapted to be rotated by the crank 9, is a pinion 12 105 which meshes with a spur gear 13, said spur gear being keyed to a cam shaft 14 which

is journalled in the side frames 4 and 5. Secured to the left end of cam shaft 14 and arranged outside the side frame 4, is an eccentric 15 which has running contact with a cam lever 16. The cam lever 16 oscillates upon a pin 17 and carries a pin 18 upon which is mounted a pawl 19 provided with a hand grip 20 by means of which said pawl may be thrown into and out of engagement with a rack 21 which is reciprocably mounted on the side frame 4. Means for yieldably holding pawl 19 in engagement with rack 21, are provided by a spring 22 which has one end connected to the pawl 19 and its other end attached to a flange on the side frame 4. A dog 23 provided with a hand grip 24 is pivotally mounted on a stud 25 and acted upon by a spring 26 for holding it in engagement with rack 21. Pivotally connected at 27 to the forward end of the rack bar 21, is a cam bar 28 which may be held at a suitable inclination to the horizontal by means of a link 29 which is pivotally connected at 30 to the rear end of cam bar 28. A slot 31 in the lower end of link 29, permits a vertical adjustment of cam bar 28. The cam bar is held in any desired position by means of a thumb nut 32 which clamps the link 29 to the ratchet bar 21. A short operating rack bar 33 has a rounded lower end 34 which is adapted to bear on the inclined cam bar 28. The cam bar 33 meshes with a spur pinion 35 keyed to a shaft 36, and serves only to transmit power to said shaft 36. Near opposite ends of said shaft, are keyed thereto two additional spur gears 37 which serve to elevate racks 38 (see Figure 1). The connection between one of the racks and pinions, is shown in Figure 6. The upper ends of the rack bars 38 are attached to a table or platen 40 so that as the cam bar 28, shown in Figure 5, is moved forward, the table or platen 40 is gradually elevated for a purpose to be hereinafter explained. As shown in Figure 3, the platen or table 40 is in the present embodiment of my invention, provided with a plurality of longitudinal partitions 41, said partitions being adapted to provide suitable compartments for piles or stacks of checks or other documents which may be arranged in said compartments in any desired order. Referring now to Figures 3 to 7 inclusive, a rock shaft 42 which is journalled in the rear ends of side frames 4 and 5, has keyed thereto a lower cam arm 43 and an upper cam arm 44 which are controlled by cams 45 and 46 respectively which are keyed to the cam shaft 14. Mounted upon the rock shaft 42 are laterally spaced lever arms 47 and 48 within the upper ends of which is journalled a secondary rock shaft 49 which is adapted to rock on its own axis while said axis is being moved to and fro in a

direction longitudinal to the feed. According to the present embodiment of my invention, five reciprocating bucklers 50 are pivotally mounted upon the secondary rock shaft 49, the lateral disposition of said grippers corresponding to the compartments which contain the checks or other documents C. The forward ends of the bucklers 50 are provided with weights 51, said weights being adjustable along the bucklers 50 and held by set screws 52 in any positions to which they may be adjusted. The downwardly deflected end of each of said bucklers 50 is provided with a friction pad 53 for adapting it to displace a check or document from the top of the pile or stack. Adjacent opposite sides of the machine are a pair of levers 54 which are keyed to the secondary rock shaft 49 and carry in their forward ends a bar 55 which is adapted to engage the under edges of the bucklers 50 for lifting them from the documents at certain times in the feeding operation. Projecting rearwardly from the rock shaft 49 and keyed thereto is a lever arm 56 which is pivotally connected at 57 to the upper end of a connecting rod 58. Said rod 58 is provided with a slot 59 in its lower end through which projects a stud 60, carried by the rearwardly projecting arm of a cam lever 61 which oscillates about the axis of rock shaft 42. This construction permits the rock shaft 49 to be turned sufficiently to raise all the arms or bucklers 50 out of the way, for introducing the checks C into the machine. The cam lever 61 is moved by a cam 62.

Referring more especially to Figures 6 and 7, a cam 63, which is keyed to the cam shaft 14 operates upon one end of a cam lever 64 which is pivoted on a stud 65 and provided with a spring 66 which holds the cam lever in running engagement with the cam 63. The forward end of the cam lever 64 is connected by a link 67 with a reciprocable slide 68 provided at its upper end with a rack 69 which meshes with a spur pinion 70, said spur pinion being keyed to a transverse shaft 71 which carries a plurality of movable stops 72 which are periodically moved into and out of the position shown in Figure 6 in which they hold the forward edges of the checks or documents C while they are being buckled in the manner indicated in Figure 6. After each group of five checks or documents has been thus buckled and before their rear edges are released by the bucklers 50, the upward movement of the slides 68 serves to move the stops 72 to release position in which their forward edges are caused to project as shown in Figure 7. After the top checks or documents have been thus separated from the pile, they are gripped by suitable grippers which are now to be 130

described. As shown in full lines in Figure 3 and in dotted lines in Figure 4, a bracket or hanger 73 carries a stud 74 on which is pivotally mounted a cam lever 75, said cam lever being provided with a cam roller 76 which travels in a profile cam slot 77 formed on the inner surface of gear 13. Cam lever 75 is connected by a link 78 to the rear end of a rack bar 79 which, as shown in Figure 8, is reciprocably mounted on a guide bar 80. The reciprocable carriage upon which are mounted the document grippers, comprises a spur gear 81 which is keyed to a shaft 82, said shaft 82 having also keyed thereto oppositely arranged spur gears 83, 83 which mesh with fixed racks 84, 84. The shaft 82 is journalled within a tubular bar 85 which is rigidly connected to a tubular bar 86 by means of side frames 87. Said carriage is supported independently of the gears and racks by means of rolls 88, 88 journalled on opposite ends of shaft 82 and on opposite ends of tubular bar 86. Said rolls 88 run on tracks 89, 89. In the present embodiment of my invention, five document grippers are mounted on the carriage and arranged to correspond to the relative positions of the piles or stacks 30 from which the documents are to be fed off. Each of said grippers includes a plate 90 supported by the tubular rods 85 and 86, said plate being provided with a downwardly presented jaw 91. A movable gripper jaw 92 is formed by the deflected lower end of a bar 93 which is movably connected to the plate 90 by a link 94 and one arm of a lever 95. Said lever 95 is fulcrumed at 96 upon an upwardly projecting portion of the plate 90. A spring 97 tends to retain the movable gripper jaw in close contact with the fixed gripper jaw. Journalled in the carriage side bars 87, 87, is a rock shaft 98 which extends through the plates 90. Secured to said rock shaft are lever arms 99 which are respectively provided with pins 100 adapted to engage cam surfaces 101 formed on levers 95. Depending from the rock shaft 98 is an arm 102 which is adapted to rock said shaft by having its travelling movement with the carriage intercepted by fixed and movable stops. As shown in Figures 2 and 8^a, one of the fixed stops is disposed at 103 adjacent the rear end of the carriage movement while a second fixed stop 104 is disposed adjacent the end of the longer forward movement of said carriage. Interposed between these fixed stops, is a movable stop 105 (see Figures 1 and 5) which is pivotally connected at 106 to one arm of a cam lever 107 which is fulcrumed on a stud 108 in the side frame 4. A cam 109 (see Figure 3) is provided with suitable connections for operating cam lever 107. In order that the operator may be kept informed of the feeding action of the carriage, suitable means are provided for each gripper to indicate whether more or less than one check is being fed off by that gripper. For this purpose, in the present embodiment of my invention, a cross bar 110 is mounted upon laterally spaced links 111 to be moved into and out of operative position on studs 112. Mounted on the cross bar 110, are a plurality of lamps 113, one terminal of each of said lamps being connected by a wire 114 to one pole of a battery 115. The other terminal of each lamp is electrically connected to a spring bar 116 which projects forwardly from the cross bar 110. The spring bars 116 are adapted to yieldably engage contacts 117 which extend through the blocks 118 carried by the plates 90 of the respective grippers (see Figures 8^a, 9, 10 and 11). Each of the blocks 118 carries on its opposite face, a conducting yoke 119 which is provided with an upper contact 120 and a lower contact 121, said contacts preferably being adjustable toward and away from each other. Arranged between the contacts 120 and 121 is a spring contact 122 which projects rearwardly from the cam lever 95. A wire 123 connects the spring contact 122 to the other pole of battery 115 so that whenever the spring contact 122 is moved into engagement with either of the contacts 120 and 121 while the carriage is in its rearmost position, an energizing circuit is completed which includes lamp 113, wire 114, battery 115, wire 123, spring contact 122, contact 120 (or 121), yoke 119, contact 117, and band 116. Referring now to Figures 1, 2 and 12, a plurality of endless belts or chains 124 are laterally spaced on the machine to correspond to the reciprocable grippers or carriages. As shown in Figure 12, each of the endless chains 124, is provided with lugs or pushers 125 which are spaced longitudinally of the chain, a distance sufficient to accommodate successive documents therebetween. Each of said endless chains 124 runs about a rear sprocket 126 and a forward sprocket 127. The forward sprockets 127 are keyed to a common shaft 128, the left end of said shaft being provided with a pinion 129 which meshes with a gear 130 on a stub shaft 131 which carries a crank 132. The top surface of the main bed plate 133 of the machine is preferably made to extend from near the forward edge of the platen or table 40 upon which the stacks of documents are disposed. Near the end of the machine and above the main bed plate, are arranged, in the present embodiment of my invention, a group of pens 134 which are carried by a common frame 135. Connected to the frame 135, is a monitor handle 136.

136 by means of which the multiple writing instruments 134 are actuated. Leading from the forward end of the main bed plate 133, is an inner guide or plate 137 5 and spaced outwardly therefrom, a plurality of guide fingers 138. This construction provides downwardly presented chutes through which the documents from the multiple writing mechanism, are discharged 10 into pockets or receptacles formed as shown in Figures 1 and 12. A receptacle for receiving the documents thus discharged, comprises a front wall 139, bottom wall 140 and partitions and end walls 15 141, said receptacle being mounted on the forward uprights of the machine by means of bracket arms 142. In the modification shown in Figures 13, 14 and 15, a packing device is shown for handling checks made 20 of very thin paper. For this purpose, the partitions 141 are arranged to provide compartments of less width than the checks as shown in the enlarged scale views, Figures 14 and 15. The upper edges of partitions 141 are made of less thickness to form ledges or shoulders 155 upon which the lateral edges of the checks become lodged until they are pressed down on to the packs as shown in Figure 15. For this purpose, 25 a pusher cross-head 143 is connected by a rod 144 to an arm 145 carried by a shaft 146 and oscillated by a cam arm 147 which is operated by a cam 148 keyed to the cam shaft 14. Within each of the receptacles 30 or compartments is arranged a pusher board 149 which is connected to the pusher cross-head 142 by means of a pair of bars 150. The checks thus packed are slightly buckled. Briefly stated, the operation of 35 my improved machine, according to the embodiment shown on the drawings is as follows.

For example, single checks arranged in five stacks or piles upon the platen or feed 40 table 40 are to be arranged in double, transverse rows beneath the writing pens 134, said checks are then to be signed by an official who manipulates the monitor handle 136 and said checks are then to be stacked 45 within the receptacles at the end of the machine in the same order in which they were taken from the stacks at the feeding-in end of said machine. As shown in Figure 4, the cam slot 77 comprises a rearwardly presented portion located relatively near to the cam shaft 14, upper and lower portions which are near the periphery of the cam and a forwardly extending portion which is intermediate in distance between the first mentioned portion and said peripheral portions 50 of the cam slot.

As the crank 9 is turned, the cam roller 55 76 when in the position shown in Figure 4, will correspond to the reciprocating carriage or gripper in its forward position as

shown in Figure 1. Prior to the parts assuming these relative positions, the bucklers 50 have buckled the top checks of the several piles in the manner shown in Figure 6, the movable stops 72 being disposed in suitable position to hold the forward edges of the checks against displacement. As the reciprocating carriage or grippers reach their rear-most position, the movable stops 72 are swung into their lowered positions shown 75 in Figure 7 which releases the forward edges of the top checks so that as the buckled checks flatten themselves, their forward edges are extended between the gripper jaws which at that time are held in open position 80 by reason of the pendulum 102 having thrown the cam lever 99 under the cam lever 95 at the forward end of the preceding stroke. During the return stroke of the carriage or grippers, said pendulum 102 comes into engagement with a fixed stop 103, and it is moved into the position shown in 85 Figure 7, permitting springs 97 to close the several grippers. If there is a failure in any one of said grippers to grip a check 90 (as shown in Figure 10), the spring contact 122 is thrown into engagement with the lower contact 121 and the lamp 113 becomes illuminated. If, as shown in Figure 11, more than one check has been gripped by the jaws 95 of the gripper, the spring switch 122 will be held in engagement with the upper contact 120, the lamp 113 being likewise energized. Noticing the lamp or lamps, the operator, by examining the particular gripper or grippers, will see whether there is no check present or two or more checks present within each of the grippers. It will be understood from Figure 8 that gear 81 is of less pitch diameter than gears 83, 83 so that 100 the reciprocatory movements of the rack 79, are multiplied in the travel of the carriage. If the machine is operated by turning the crank 9 in a clockwise direction, according to Figure 4, the cam 77 revolves in the direction of the arrow. By noticing the form of cam 77, it will be seen that cam arm 75 has moved the carriage to its extreme forward position in which the forward fixed stop 104 operates to release a group of 105 checks. The carriage is then returned to its rearmost position shown in Figure 7 to receive another group of checks. The cam arm is next moved into a position intermediate to its extreme forward and rear positions, thus bringing the carriage forward to a position in which the movable intermediate stop 105 operates the grippers to release a second group of checks in the rear of the first mentioned group. As 110 shown in Figure 6, a cam lever 151 which is fulcrumed at 152, is operated by cam 45, said cam lever being provided with a finger or dog 153 which is adapted to lock the endless chains or belts 124 during those periods 115 120 125 130 135 140 145 150 155 160 165 170 175 180

- in which the checks are being positioned. As soon as the checks are thus arranged in order, the endless chains or belts are released so as to permit them being moved into position under the multiple writing instrumentalities. According to the present embodiment of my invention, this operation is preferably performed by a second operator who turns the crank 132. A further movement of said endless chains or belts 124, after the checks have been signed, is adapted to discharge said checks into the several compartments of the packing box wherein they are arranged in the same order in which they were withdrawn from the feed table 40.
- I claim:
1. In a machine of the character described, the combination with means for supporting a plurality of piles of documents, and means operating on said piles for separating documents therefrom and arranging successive documents of each pile in different positions with respect to said pile.
  2. In a machine of the character described, means for supporting documents in bulk, means movable towards and away from said supporting means for gripping the documents one by one, said gripping means having successive periods of travel of different lengths, for arranging the documents in a predetermined group arrangement.
  3. In a machine of the character described, the combination with means for supporting a plurality of piles of documents, of a carriage having successive periods of travel of different lengths, grippers mounted on said carriage and operating on documents in the several piles, and means for opening said grippers at the ends of their travelling periods for arranging said documents in successive groups at different distances from said document supporting means.
  4. In a machine of the character described, means for supporting a plurality of piles of documents, a carriage movable towards and away from said document supporting means, means for imparting successive movements of different extents to said carriage grippers mounted on said carriage to correspond respectively to said piles, and means for opening and closing said grippers.
  5. In a machine of the character described, means for supporting a plurality of piles of documents, a reciprocable carriage, grippers mounted on said carriage and operating respectively on said piles, stops arranged adjacent the opposite extreme positions of said carriage for operating said grippers, and a stop interposed between the first mentioned stops for operating said grippers intermediately of the other stops.
  6. In a machine of the character described, means for supporting a plurality of piles of documents, a reciprocable carriage, grippers mounted on said carriage and operating respectively on said piles, stops arranged adjacent the opposite extreme positions of said carriage for operating said grippers, and a stop interposed between the first mentioned stops for operating said grippers intermediately of the other stops.
- pers mounted on said carriage and operating respectively on said piles, stops arranged adjacent the opposite extreme positions of said carriage for operating said grippers, and a stop interposed between the first mentioned stops for operating said grippers intermediately of the other stops, said interposed stop being provided with automatically operated means for moving it into and out of operative position. 70
7. In a machine of the character described, the combination with means for supporting a pile of documents, of means operating on said pile for moving successive documents therefrom and depositing them in prearranged positions distant from said pile, and other means for conveying said documents as a group from their deposited positions. 75
8. In a machine of the character described, the combination with a support for holding a pile of documents to be fed off, a reciprocatory carriage, an oscillatory cam lever connected to said carriage, a rotary cam for operating said cam lever, said cam being adapted to impart successive throws of different extent to said cam lever, a gripper mounted on said carriage, means for closing said gripper adjacent the rear end of each carriage movement, and opening the same adjacent the forward end of each movement. 80
9. In a machine of the character described, the document separating means comprising a reciprocable gripper movable into and out of position to grip the forwardly presented edge of the top document of a pile, means for blocking the movement of the forward edge of the top document, means for buckling said top document, said blocking means being movable to a position to permit the forward edge of the top document to be presented to the gripper and means for opening said gripper at one end of its reciprocatory movement for releasing a sheet which has been retracted from the pile and closing said gripper at the other end of its reciprocatory movement for gripping the forward edge of said top document. 85
10. In a machine of the character described, document separating means comprising a gripper movable into and out of position to grip the forwardly presented edge of the top document of a pile, a stop movable into the path of the forward edge of the top document, means for buckling said top document, means for moving said stop to permit the forward edge of the top document to be presented to the gripper, and means for closing said gripper, said buckling means comprising a primary rock shaft, a secondary rock shaft journaled in said lever arms, oscillatory bucklers coaxially mounted with said secondary rock shaft, a cam lever keyed to said primary rock shaft, levers keyed to 90
- 115
- 120
- 125
- 130

- said secondary rock shaft, a connecting rod extending between said lever on the primary rock shaft and one of the levers on the secondary rock shaft, and a rod carried by the 5 levers on said secondary rock shaft for movably engaging said bucklers.
11. In a machine of the character described, means for holding a pile of sheets to be fed off, track bars extending from said 10 pile holding means, a carriage travelling on said track bars, a fixed rack, a gear journaled on said carriage and meshing with said rack, a movable rack having geared connections with the first mentioned gear, 15 a gripper on said carriage for retracting sheets from said pile, and means for reciprocating said movable rack for propelling said carriage towards and away from said pile.
12. In a machine of the character described, means for holding a pile of sheets to be fed off, track bars extending from said pile holding means, a carriage travelling on 20 said track bars, a fixed rack, a gear journaled on said carriage and meshing with said rack, a movable rack having geared connections with the first mentioned gear, 25 a gripper on said carriage for retracting sheets from said pile, and means for reciprocating said movable rack for propelling said carriage towards and away from said pile. 30
13. In a machine of the character described, means for holding a pile of sheets to be fed off, a carriage reciprocable towards and away from said pile holding means, and a gripper mounted on said carriage, said 35 gripper including relatively movable jaws, means for opening and closing said jaws at opposite ends of the travel of said carriage, and means movable into and out of the path of said carriage for opening said jaws intermediately of the extreme positions of said carriage. 40
14. In a machine of the character described, means for holding a pile of sheets to be fed off, a carriage reciprocable towards 45 and away from said pile holding means, and a gripper mounted on said carriage, said gripper including relatively movable jaws, means for opening and closing said jaws at opposite ends of the travel of said carriage, and means for opening said jaws intermediately of the ends of travel of said carriage. 50
15. In a machine of the character described, means for holding a pile of sheets, a reciprocable carriage, a gripper comprising relatively movable jaws, a lever for opening and closing said jaws for predetermined positions of said carriage, means for engaging said lever for opening and 55 closing said jaws at opposite ends of the travel of said carriage, and means movable into and out of position to open said jaws at an intermediate position of said carriage. 60
